CLAIM

The ornamental design for portable information terminal, as shown and described.

DESCRIPTION

1.-2. Portable information terminal

1.1 : Perspective

1.2 : Perspective

1.3 : Perspective view showing changed state

1.4 : Perspective view showing changed state

1.5 : Front

1.6 : Back

1.7 : Right

1.8 : Left

1.9 : Top

1.10 : Bottom

Each of design 1 is a portable information terminal functioning as a computer, a media reproducing device (e.g. a musical player, a video player, a game machine), a media storage device, a communication equipment (e.g. a mobile phone), etc.; the portable information terminal comprises connected first to third housing and a flexible display portion supported by the first to third housings; the two-folded state,

(Continued)

the unfolded state, or the state bent in an arbitrary shape, as seen in the reproductions 1.1 to 1.11.

1 Claim, 10 Drawing Sheets
